WALTER BIXBY, OF BOSTON, MASSACHUSETTS, ASSIGNOR TO SHAWMUT ENGINEERING COMPANY, OF BOSTON, MASSACHUSETTS, A CORPORATION OF MASSACHUSETTS

YARN SPOOL FOR TUBE FRAMES AND THE LIKE

Application filed November 4, 1927, Serial No. 231,005. Renewed January 26, 1929.

This invention relates to yarn spools and is devised particularly to suit certain requirements of tube frames for yarn spools acting as carriers of the supply of yarn.

One object of the invention is to provide the spool barrel with easily detached end heads which shall, when in use, be firmly and securely fastened to the spool barrels but admit readily of substitution or interchange of new heads when desired for any reason. A further object of the invention is to provide a yarn spool construction admitting of quick adaptation to different positions or relations in a multiple spool frame so that a spool intended for a single tube frame may be readily adapted for use in a multiple spool frame to fit the middle bearing extension carried by such frames as well as permit the reversal of the independent spools or sections of the multiple spool tube frame.

In its more important features, the invention comprises a yarn spool whose barrel has hollow ends containing internal anchoring discs or members securely fastened inside in conjunction with detachable end heads and clamping journal members having inward threaded or interlocking extensions for engaging the interior anchoring members so as to permit detachment and substitution of either end head or of either journal member to adapt the spool for use in any pair of bearings in which it may be desired to insert the same for service. Provision is also made to positively prevent rotation of the detachable head in relation to the barrel or the anchoring member. These and other features of the invention will be particularly described in the following specification and will be defined in the claims hereto annexed.

In the drawings I have illustrated a simple and convenient form of construction and arrangement embodying the principles of this invention in which Figure 1 is a front elevation showing the sections of a spool equipped with my invention, principally in vertical

central section and mounted in a multiple tube frame.

Figure 2 comprises detailed side elevation and end views of one of the detachable journal members employed.

Figure 3 shows in end and in side elevation the cooperating journal member adapted to interlock with that shown in Figure 2.

Figure 4 shows the interlocking member for preventing rotative displacement, in a side elevation, end elevation and plan view respectively.

Figure 5 shows in plan view and also edge-wise the form of interlocking member used for the interior or middle bearing journal to prevent rotative displacement.

In Figure 1 I have shown a multiple tube frame embracing the longitudinal carrier bar *b* having end brackets *c* for the suspension of the tube frame from its carrier chains and also for supporting the outside journals of the sectional spool. One or more intermediate spool bearing brackets *d* of any well-known type may be used to support the interior chains of the spool.

The spool barrel *a* may be made of a tubing of appropriate length or, as shown at *a'* the spool barrel for the greater parts of its length may be made of wood with projecting hollow supporting ferrules secured to each end so that in either case the spool has barrels with hollow ends into which is inserted an appropriate anchoring member, preferably comprising a flanged disc or diaphragm 1 fastened by spot welding or soldering to the interior wall of the hollow barrel member. These anchoring members 1 are formed with central apertures which, in the form shown, are screw threaded to form interlocking and adjustable engagement with inserted journal screw members 3 and 4, whose heads respectively engage the centrally apertured inner portions of the end heads 2, either directly as shown at the left of Figure 1 or through the medium of an interposed annular journal 90

member 4^a or 4^b as shown at the middle part of Figure 1. In both cases the end heads 2 are preferably provided with interior bosses, hubs or shoulders, 2^a, adapted to fit snugly 5 inside the hollow end of the spool barrel so that when the journal screw 3 or 4 is inserted and interlocked with the threaded aperture of the anchoring members 1, the end heads will be clamped into firm abutment against 10 the end edges of the barrel.

Where the journal at one or both ends is to be in the form of a reduced pintle 3^a, forming an outward extension of the threaded journal screw, the screw and the journal member may be made in one piece. Where, however, the journal member is to fit the interior bearing extension of the tube frame, I prefer to make the journal member separate from the threaded extension thereof. In such 20 case, the journal member preferably comprises an annular tubular or cup like bearing journal 4^a having a peripheral flange externally notched to receive a member for locking it against accidental rotation independent of 25 the spool, as will presently be explained.

Often times it is desired that the abutting journal members of adjacent sections of the tube frame spool shall have an interlocking engagement to produce uniform and equal 30 rotation of both sections. When this is desired, one of the cup like members 4^a may be provided with tongue receiving notches 4^a formed in its outer end edge. The other annular bearing member 4^b is provided with 35 corresponding lugs or tongues 4^c adapted to engage diametrically opposite slots 4^d to form an interlocking engagement. These separable annular journal members are both held in place by similar journal screws 4 and are 40 preferably locked with the spool body as will now be explained.

Each anchoring member 1 is provided at its periphery with a radial slot or notch at a corresponding distance from the center. The 45 end heads 2 have a similar radial notch as has also the peripheral flange of the journal members 4^a, 4^b. When the end head and the annular bearing extension are assembled preparatory to drawing them tightly to an operative 50 position by means of the attaching journal screw 4, the slots 2^e of the end heads and the notch 4^e of the annular journal members should be aligned with the slot 1^a of the anchoring member and before the parts are 55 telescoped together, there should be inserted between them a gib or key 6 in the form of a cross having four substantially equal arms of which the axially extending arms telescope into the slots 1^a, 2^e, while the transverse arms 60 form a spacing means that prevents the axial displacement of the key or interlocking member when the parts are assembled in firm relationship. Since the anchoring member 1 is securely fastened to the interior of the 65 barrel, it is evident that no rotation of the

head or of the journal extension with relation to the anchoring member of the barrel can take place. Yet this does not in the least interfere with the assembling or disassembling of the device.

For anchoring the outer end heads about 70 the one-piece journal member 3, I employ an interlocking member, or key, of the form shown in Figure 4, in which there are provided at diametrically opposite points on the small disc 7 interlocking tongues 7^a and intermediate of these two tongues on the outer side of the disc are provided spacing lugs 7^b. The tongue 7^a projects outwardly into the slot 2^e of the end head, while the inwardly turned lug 7^b projects into the slot 1^a in the anchoring member 1. The lug 7^b prevents endwise displacement that would permit disengagement of the inwardly projecting interlocking tongue, and thus the outer end head is securely locked against rotation with relation to the spool barrel.

Should it be desired for the purpose of reversing the pattern to reverse the ends of the two outside spool sections, it will be obvious that the spool journals 4, 4^a, with their corresponding locking keys, can be interchanged end for end with the one-piece spool journal member 3 and its locking key by merely retracting the screw journals and 95 their associated locking keys and substituting one for the other.

One of the great advantages of this construction and arrangement resides in the fact that it is unnecessary to carry a large number of spools of the same pattern to meet the requirements of the various pattern demands that may be met with, since any spool on which the yarn is wound in a definite pattern can be substituted in any position in 100 either direction in a multiple spool frame and can also be used in a single spool tube frame by merely changing the journals.

Furthermore, as the end head, the barrel and the journal of each spool is each liable 110 to injury or damage that unfits it for further use, replacement of any one of these parts when damaged can be readily effected, while preserving the uninjured parts for further use, thereby securing great economy in maintaining the spools at full efficiency.

The flanged or hollow construction of the anchoring members is a feature of particular importance in the manufacture of these spools because it facilitates a very effective 120 welding of the anchoring member by allowing one of the welding electrodes to be inserted against the inside of the flange, while the other electrode is brought into contact with the opposite spot on the outside of the barrel, thus causing the welding current to flow directly through the two contacting parts and thus accomplishing a perfect weld which is far superior to any spot welding operation that can be performed with a solid 130

disc with both electrodes or terminals pressed against opposite sides of the same member, namely, the barrel.

What I claim is:

5 1. A yarn spool for tube frames embracing in combination with a tubular barrel member, a centrally apertured anchoring member secured interiorly and transversely thereof, a detachable end head adapted to abut against 10 the end edge of said barrel member, a head attaching member passing axially through said end head and having its inner end releasably engaged with the apertured anchoring member and having an axial extension 15 projecting outside said end head, thereby permitting removal and replacement of journals and heads on the same spool.

2. A yarn spool for tube frames embracing in combination with a barrel having hollow 20 ends, centrally apertured and internally threaded transverse disks secured to the interior wall of said barrel ends, end heads adapted to abut against said hollow ends, axially disposed journal screws whose inner 25 ends have adjustable threaded engagement with said disks to draw the end heads firmly but releasably against the end edges of the barrel, the journal screws being provided with axial outwardly projecting extensions 30 forming bearing journals to rotatably support the spool in its bearings.

3. A sectional spool for a tube frame embracing longitudinal spool sections having tubular ends in which are secured transverse 35 anchoring members, end heads abutting against adjacent ends of the sections, axially disposed annular coupling members projecting outwardly from the end heads to form mutually interlocking spool supporting journals, and axially disposed means for detachably securing the coupling members and the end heads to said anchoring members.

4. A sectional spool for a tube frame embracing longitudinal spool sections having 45 tubular ends in which are secured transverse anchoring members, end heads abutting against adjacent ends of the sections, axially disposed annular coupling members projecting outwardly from the end heads to form 50 mutually interlocking spool supporting journals, and axially disposed means for detachably securing the coupling members and the end heads to said anchoring members, and means for interlocking the end heads with the 55 anchoring disks to prevent rotative displacement of the end heads in relation thereto.

5. In a yarn spool, the combination with a spool barrel having hollow ends, in which are secured transverse centrally apertured 60 anchoring disks, end heads having annular shoulders fitting inside said hollow ends, axial head attaching screws passing centrally through said heads and having releasable threaded engagement with the interior anchoring members, said attaching screws be-

ing provided with axial outwardly projecting journal forming extensions for rotatably supporting the spool.

6. The combination with a spool barrel having hollow ends, transverse anchoring members secured therein, end heads abutting against the hollow ends of the barrel, journal members releasably engaged with said anchoring members for securing said heads in such abutting position, interlocking members 70 interposed between the end heads and the transverse anchoring members and forming interlocking engagement between each end head and its anchoring member to prevent rotative displacement of the end head.

7. An end bearing construction for a yarn spool embracing in combination a tubular barrel member, a transverse perforated anchoring member secured therein, a centrally perforated end head abutting against the end 80 edge of the barrel, journal carrying attaching means for releasably securing end head and the anchoring member together, an interposed locking member arranged to project through both the end head and the anchoring 85 member at a distance from the centres thereof, said locking member being provided with means to prevent its accidental displacement from locking position.

8. In a yarn spool the combination with a longitudinal barrel, an annularly flanged anchoring member located inside the hollow end portion of the barrel and welded thereto, a detachable end head having an inwardly offset shoulder adapted to fit inside the hollow 100 end of the barrel to position the head concentrically therewith, an axially disposed removable fastening member passing centrally through said head and having threaded engagement with a co-axial portion of the anchoring member, said fastening member being provided with an axial extension outside 105 of the head to form a supporting journal for the head.

9. A yarn spool embracing in its construction a longitudinal barrel, a transverse anchoring member fixedly secured inside the end portion of said barrel, an end head provided with an inwardly offset annular positioning shoulder adapted to engage the interior end edge of the barrel, a removable fastening member passed through the center of the head from the outside and having releasable fastening engagement with the anchoring member, and means for positively interlocking the end head against rotative displacement on the barrel.

10. In a yarn spool the combination of a longitudinal barrel, an annular anchoring member secured therein, said anchoring member being provided with a peripheral flange for securing it to the barrel and with an inner flange provided with a screw thread, an end head formed with an annular positioning shoulder adapted to fit inside the end 125

of the barrel, means for releasably anchoring the end head to the anchoring member, and means for interlocking the end head against rotation with relation to the barrel.

5 11. A yarn spool element comprising a tubular barrel having an interior anchoring member fixedly secured inside its end portion, said anchoring member being formed with an offset peripheral flange for securing it to the barrel and with an interiorly disposed offset flange that is threaded to receive a head attaching screw and having also an off center notch adapted to receive means for interlocking an attached head against rotation.

10 15. In witness whereof, I have subscribed the above specification.
